(57) CLAIM

The ornamental design for a garment, as shown and described.

DESCRIPTION

FIG. 1 is a front perspective view of a garment showing our new design.

FIG. 2 is a front view of the garment.

FIG. 3 is a rear view of the garment.

FIG. 4 is a right-side view of the garment.

FIG. 5 is a left-side view of the garment.

FIG. 6 is a top view of the garment.

FIG. 7 is a bottom view of the garment.

FIG. 8 is a front perspective view of the garment shown in an alternate configuration in a state of use.

FIG. 9 is a cross-sectional view of the garment taken in the direction of line 9-9 of FIG. 4.

FIG. 10 is a cross-sectional view of the garment taken in the direction of line 10-10 of FIG. 4; and,

FIG. 11 is a cross-sectional view of the garment taken in the direction of line 11-11 of FIG. 2.

The short broken lines showing elements of the garment in the drawings illustrate portions of the garment that form no part of the claimed design. The human figure rendered in short broken lines in FIG. 8 illustrates environmental subject matter intended to assist in showing how the design appears when in use and forms no part of the claim.
